CLAIM

The ornamental design for a mixed reality vehicle simulator as shown and described.

DESCRIPTION

FIG. 1 is a perspective view of a mixed reality vehicle simulator of a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top rear perspective view thereof;

FIG. 9 is a bottom front perspective view thereof;

FIG. 10 is a perspective view of a mixed reality vehicle simulator of a second embodiment of our new design;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a top rear perspective view thereof; and,

FIG. 18 is a bottom front perspective view thereof.

The features of the mixed reality vehicle simulator shown in broken lines in the figures form no part of the claimed design.
